UNITED STATES PATENT OFFICE.

RAY E. ELLIS, OF WICHITA, KANSAS, ASSIGNOR TO THE COLEMAN LAMP COMPANY, OF WICHITA, KANSAS, A CORPORATION OF KANSAS.

FOLDING CAMP-STOVE OVEN.

Application filed August 23, 1924. Serial No. 733,755.

To all whom it may concern:

Be it known that RAY E. ELLIS, a citizen of the United States, residing at Wichita, in the county of Sedgwick and State of 5 Kansas, has invented new and useful Improvements in Folding Camp-Stove Ovens, of which the following is a specification.

The present invention relates to camp stoves of the portable type, and more particularly to ovens intended for use in connection with such stoves.

An object of the invention is to provide in connection with a camp stove an oven of knock-down or collapsible construction, 15 which may be readily folded within the case for the stove or set up for use in conjunction with the stove.

A further object of the invention is to provide within the oven, and preferably secured permanently thereto, an article supporting grate or shelf, which may be readily folded with the oven structure without detachment therefrom.

The invention also seeks to provide a deflecting plate adapted to be positioned above the burners of the stove or to be folded against one of the side walls of the oven when the latter is not in use, or is collapsed for transportation of the stove.

30 The invention also relates to details of construction of the oven, and has other objects, which will become apparent as the description proceeds in connection with a preferred embodiment disclosed in the accompanying drawings, wherein:

Figure 1 is a perspective of the stove and oven set up for use.

Figure 2 is a perspective showing the structure collapsed.

40 Figure 3 is a vertical section on the line 3—3 of Figure 4.

Figure 4 is a longitudinal section on the line 4—4 of Figure 3.

Referring to the drawings for a more 45 detailed description, 10 indicates a stove case having positioned within the same the usual burners 11 and provided with supporting legs 12 which may be folded against the bottom of the case.

50 The top edge of the case is provided with inturned flanges 13 which support a plate 14 having openings to receive the burners 11.

55 Since the invention does not relate to the construction of the burners or of the case

proper, no further description is thought necessary, as devices of this character are old and well known in the art.

Above the case is positioned an oven structure having a side wall 15 hingedly connected at 16 to the case by means of brackets 17. The wall 15 has hingedly connected thereto a top wall 18 by means of a hinge joint 19, and the forward edge of the top wall 18 has connected thereto by 60 means of a hinge joint 20 a side wall 21, the lower edge of which is inturned to form a flange 22 adapted to rest upon the plate 14 when the oven is in operative position, as indicated in Figures 1 and 3. The oven 65 is also provided with an end wall 23 suitably hinged at its rear edge to the back side wall 15 by means of a hinge joint 24 (Figure 3). The opposite end wall is horizontally divided to form two doors 25, 26, 70 both of which are hinged at 27 to the side wall 15. The closure 26 has an interior flange 28 adapted to engage a complementary flange 28' formed on the side wall 23 and the door 25 has a locking flange 29 75 so adapted to engage the top edge 26' of the closure 26.

When in use, the oven is set up in the position shown in Figures 1 and 3, but when the stove burners are to be employed without the oven, the latter may be swung bodily to the position indicated in dotted lines in Fig. 3 in which position it is supported by legs 30 pivoted at 30' upon the top wall 18. For supporting articles within the oven 80 above the burners there is provided a substantially rectangular grate or platform 31, suspended from the top wall 18 by means of jointed hinge brackets 32, each of which is formed in two sections adapted to be 85 folded one over the other, as indicated in Figure 3, which shows the oven swung back from over the burners. The brackets are pivotally connected to the wall hinges 19 and 20 so that both sections may be folded 90 against the wall, together with the grate 30, when the latter is not in use. Obviously 95 when the oven is set up, the grate will drop automatically to position spaced from the wall 18, due to the free joint in the hinge 100 brackets and the pivotal connections of the same with the oven wall of hinges. It will 105 be understood, of course, that when using the term "grate" in the description and claims, there is no intention of limiting the 110

structure in either the claims or the specification to an open support for articles or one of the exact structure shown and described.

5 In order to prevent direct application of the flame or heat from the burners to articles supported on the grate 31, a deflecting plate 33 may be positioned directly above burners and the same provided with arms 10 34 pivotally connected at 35 to the wall 15 of the oven. It will be noted that this point of pivotal connection is such that the plate may be folded against the wall 15 when the oven is collapsed or is moved to inoperative 15 position, as indicated in Figure 3.

Because of the permanent connection of the grate 31 and deflecting plate 33 with the oven structure, there is no danger of loss of these parts and they do not interfere in 20 any way with the collapsing or setting up of the oven. Both the plate and the grate may be folded against the walls of the oven when the latter is not used and when the stove is to be transported both parts may 25 be conveniently assembled with the oven structure.

In Figure 2 the device is shown in knocked-down or collapsed state. In order to obtain this arrangement of parts, the 30 oven is first moved to the inoperative position shown in Figure 3. In such position both the grate and the deflecting plate are moved against the walls 15 and 18 respectively of the oven. The side wall 21 is then 35 swung downwardly over the grate 30 and both of these walls may be then folded downwardly over the side wall 15. The end walls 23 and 25, 26 may each be subsequently folded inwardly over the remaining walls 40 which have been superposed. In the position thus obtained by collapsing the entire oven structure, the side wall 15 constitutes a top for the casing, and as will be noted from Figure 2, it is provided with the 45 hinged fastener 36 adapted to engage a lug 37 on the case.

Obviously, the invention is not limited to the details of structure illustrated and described, the gist of the invention being the 50 provision of a collapsible oven structure having in association therewith a deflecting plate and grate which are preferably secured permanently to portions of the oven and may be freely collapsed therewith. I 55 am aware that it is broadly old to provide a collapsible oven for a portable stove, but of different structure from that illustrated and described, and so far as I am aware there has never been devised a construction 60 including as a part thereof a supporting grate permanently secured to the oven and collapsible therewith. Nor has a deflecting plate for use in conjunction with such a 65 grate been permanently secured to the oven in such a manner that it does not interfere

with the arrangement of the oven parts in a compact readily transportable structure such as I have provided.

I claim:

1. In a device of the class described, a 70 burner carrying case and a collapsible oven structure hinged to said case, said structure including side walls, end walls, and a top wall all hingedly and permanently connected and adapted when the oven is collapsed to be folded over one another, an article supporting shelf permanently connected to one of said walls and adapted to be moved against said wall when the oven is collapsed, and means permanently connecting said shelf to the wall, said means serving to permit the shelf to be moved away from the wall and operable to limit said movement and wholly to support the shelf above the burner case. 85

2. In a device of the class described, a burner carrying case and a collapsible oven structure hinged to said case, said structure including side walls, end walls, and a top wall all hingedly and permanently connected, 90 and adapted, when the oven is collapsed, to be folded over one another, an article supporting shelf connected to one of said walls and adapted to be moved against the same when the oven is collapsed, and means connecting said shelf to the wall, said means being positioned between the shelf and the wall when the shelf is moved against the latter and serving to limit the movement of the shelf away from the wall and wholly to support the shelf above the burner casing. 95

3. In a device of the class described, a burner carrying case and a collapsible oven structure hinged to said case, said structure including side walls, end walls, and a top 105 wall all hingedly and permanently connected and adapted, when the oven is collapsed, to be folded over one another, an article supporting shelf connected to one of said walls and adapted to be moved against the same 110 when the oven is collapsed, and means connecting said shelf to the wall, said means being positioned between the shelf and the wall when the shelf is moved against the latter and serving to limit the movement of the shelf away from the wall and wholly to support the shelf above the burner casing, 115 said supporting means comprising arms hingedly connected to one another and to the oven wall. 120

4. A device, as specified in claim 2, including a deflecting plate positioned directly above the burner case and hingedly connected to one of the oven walls, said plate being adapted to be moved against an oven 125 wall when the device is collapsed.

5. In a device of the class described, the combination of a burner carrying case and a collapsible oven structure including hinged- 130 ly connected walls adapted to be positioned

- over said case, an article supporting shelf permanently connected to one of the oven walls and adapted to be moved against the same when the oven is collapsed, and hinged 5 arms permanently connecting said shelf to the wall, said arms serving to permit the shelf to be moved away from the wall and operable to limit said movement and wholly to support the shelf over said case.
- 10 6. In a device of the class described, the combination of a burner carrying case and a collapsible oven structure including hinged- ly connected walls adapted to be positioned over said case, an article supporting shelf
- permanently connected to one of the oven 15 walls and adapted to be moved against the same when the oven is collapsed, and hinged arms permanently connecting said shelf to the wall, said arms being positioned between the shelf and the wall when the shelf 20 is moved against the latter and serving to limit the movement of the shelf away from the wall and wholly to supprt the shelf in operative position above said case.
- In testimony whereof I have hereunto set 25 my hand.

RAY E. ELLIS.
